UNITED STATES PATENT OFFICE

EDWIN J. DREISBACH, OF NEW HAVEN, CONNECTICUT

CUSHION DEVICE FOR WATER CLOSET BOWLS AND THE LIKE

Application filed July 23, 1930. Serial No. 470,105.

This invention relates to an improvement in cushion devices for water-closet bowls and the like, and particularly to devices designed to act as a cushion between such bowls and the pivotal seat-member thereof.

The main object of this invention is to provide at a low cost for manufacture, a simple, convenient and effective device of the class described which may by any person however unskilled be applied to and removed from the rim of a toilet-bowl and laterally shifted thereupon according to the shape thereof, without the use of a screw driver or other tool.

With the above and other objects in view as will appear from the following, my invention consists in a cushion device for water-closet bowls and the like having certain other details of construction and combinations of parts as will be hereinafter described and particularly recited in the claim.

In the accompanying drawings:

Fig. 1 is a fragmentary view, partly in elevation and partly in section, of a water-closet bowl upon which my improved cushion device has been installed, together with the seat and cover-member thereof;

Fig. 2 is a detached perspective view of one form which a cushion device embodying my invention may assume;

Fig. 3 is a view thereof in transverse section taken on the line 3—3 of Fig. 2;

Fig. 4 is a view thereof in longitudinal section taken on the line 4—4 of Fig. 2;

Fig. 5 is a perspective view of the cushion block detached;

Fig. 6 is a corresponding view of the strap-member;

Fig. 7 is a face view of another form of cushion device embodying my invention;

Fig. 8 is a side view thereof; and

Fig. 9 is an edge view of the cushion-block shown in Figs. 7 and 8, detached.

In carrying out my invention as shown in Figs. 2 to 6 inclusive, I employ a cushion-block 10 formed of rubber or other resilient material and provided in its under-face with a transverse dovetail or undercut groove 11 adapted to receive the central portion of a retaining-strap 12, the respective opposite ends of which project beyond the cushion-

block 10 and constitute flexible retaining-arms 13 and 14 respectively.

The retaining-arms 13 and 14 above referred to are preferably set downward with respect to the central portion of the retaining-strap 12, as shown in Figs. 4 and 6, and are adapted to be bent into the clasp-like form shown in Fig. 1, whereby they are enabled to grip the top flange 15 of a toilet-bowl 16 and thus maintain the cushion-block 10 upon the upper face of the said flange in position to cushion the seat-member 17 and prevent the same from slamming upon the bowl proper.

Preferably, the dovetail-groove 11 in the under-face of the cushion-block 10 is so proportioned that it will snugly grip the opposite edges of the central portion of the retaining-strap 12, though this feature is not essential, since when the device is once in place, the said cushion-block will remain in the desired position.

By providing the cushion-block 10 with an undercut or dovetail-groove, the attachment thereto of the retaining-strap 12 is very much facilitated, with a corresponding decrease in cost for manufacture.

If desired and as shown in Figs. 7, 8 and 9, I may provide the cushion-block 10 with a transverse passage 18 (Fig. 9), through which the strap member 12 may be passed in such manner as to leave its retaining-arms 13 and 14 projecting from the opposite sides of the said cushion-block.

It is obvious without further illustration that the cushion-block may be molded in place if desired.

The retaining-arms 13 and 14 are preferably made integral with each other by forming them at the respective opposite ends of a retaining-strap, as shown, but if desired may be formed distinct one from the other. The retaining-arms are preferably made of non-corrosive material, such as brass, zinc or stainless steel, though many other materials are obviously available for the purpose.

It is intended, under ordinary circumstances, to supply the cushion devices to a purchaser with the retaining-arms 13 and 14 unbowed, so that they may be bent as re-

quired to accommodate between them bowl-flanges 15 of different forms and sizes, though I wish to have it understood that, if desired, the arms may be previously bent into clasp-like form as indicated by broken lines in Fig. 4, before being supplied to the purchaser in readiness to be snapped in place.

It will be understood by those skilled in the art that my invention may assume varied physical forms without departing from my inventive concept, and I, therefore, do not limit myself to the specific embodiments herein chosen for illustration, but only as indicated in the appended claim.

I claim:

15 As a new article of manufacture; a removable and laterally-shiftable cushion-device for toilet-bowls, consisting of an oblong cushion-block of resilient material having a 20 passage extending therethrough in the direction of its minor axis; a strip of flexible sheet-metal extending through the minor-axis passage in the said cushion-block and projecting therefrom on opposite sides thereof to provide a pair of complementary oppositely-extending flexible arms adapted to be reversely-bowed for clasping the rim of a toilet-bowl 25 from which the device is removable and replaceable at pleasure and laterally-shiftable with respect thereto without the use of tools.

30 In testimony whereof, I have signed this specification.

EDWIN J. DREISBACH.
